TYPEWRITER

Alfred Vogt, Chemnitz, Germany, assignor to
 Wanderer-Werke vorm. Winklhofer & Jaenicke
 Akt.-Ges., Schonau-Chemnitz, Germany

Application October 28, 1932, Serial No. 640,106
 In Germany August 21, 1931

13 Claims. (Cl. 197—25)

This invention has for its object to provide a typewriter of maximum noiselessness permitting a rapid key action and yet having great simplicity of construction and durability.

5 Noiseless typewriters are known having type bars each supported by two links and whereof the types are relieved from key action at the printing point and are caused to print by momentum. In such machines equipped with a simple 10 platen shift, each type bar carries a plurality of type groups, for example two groups, each having two types so arranged that two key levers are associated with each type bar. In order to selectively print one or the other type group, means 15 are provided for shifting each type bar into another path between normal and printing position when striking one of the two keys associated therewith. To achieve this, separate shift members are necessary, which on striking the different keys associated with one type bar, influence 20 in different ways at least one of the two links supporting the type bar. In the known machines this result is achieved by providing that the joint of one of the links is movable. This arrangement has the disadvantage that the drive and 25 transmission members between the keys and the type bars are greatly complicated and have to be of expensive construction. The wear of the many small and delicate parts and their bearings 30 is also so considerable that these machines have a short life and are not economical.

The present invention has for its primary object to overcome the said disadvantage in a typewriter having type bars each supported by two links and whereof the types are relieved from key action at the printing point and are caused to print under momentum. The main feature of the present invention consists in that the type bars each carry two types and are each actuated 35 by a single key through drive and transmission members and are so arranged in their normal position that the type heads lie in an approximately horizontal plane in front of the platen axis and occupy an arc of approximately 90°, the 40 radius of which arc is a function of half the number of types, the width of the type heads, and their minimum separation from each other, and the type bars being so guided by the links that the types move in an approximately linear path 45 to the printing point.

In a modified construction according to this invention there is obtained a better utilization of the space required to accommodate the movements of the type bars and the links supporting them, whereby the machine can be made smaller 50

in size. Furthermore, in this modification the type bars are given a very precise guiding during their entire printing movement, lateral deviation of the type bars being prevented, and the impact of the types against the platen taking place 5 exactly in the axis of the same.

These advantages are achieved essentially by so arranging the links and their joints that the middle and rear parts of the type bars during their movement from the position of rest or normal position to printing position traverse an arc-shaped path, while the types traverse a linear path.

The invention enables the printing mechanism of the typewriter to be of exceedingly simple construction and to occupy a very small space. Also the manufacture is rendered more economical and the assembly of the drive and transmission members is made easier. The machine can also be more easily kept in good condition and has a 20 long life of reliable operation. The typewriter according to the present invention also permits high speed of operation with extreme silence of the entire mechanism and of the printing. Exceedingly sharp and clear impressions of the type, and a 25 large number of good copies, are obtainable.

The drawings illustrate diagrammatically as side views three constructional examples according to the invention, in which:

Figure 1 shows the first constructional form 30 with the parts in position of rest or normal position.

Fig. 2 shows the same construction in the position in which the type bars are relieved from the action of the keys and are automatically further 35 advanced by momentum,

Fig. 3 shows the parts in position when the types strike the platen,

Figs. 4, 5 and 6 show corresponding positions of the various parts in the second constructional 40 form,

Fig. 7 shows another constructional form with the parts in position of rest or normal position, and

Fig. 8 shows the same with the parts in striking 45 position.

In the first two forms of construction, each type bar 1 is supported by two links 3 and 5. The front link 3 is pivoted at 4 to the machine frame, and the rear link 5 is pivoted at 6 to a bracket 7. 50 The links 3 and 5 are jointedly connected to the type bar 1. According to the invention, the type bars 1 each carry two type characters 2 and are each actuated by a single key 14a. On striking the key 14a, a key lever 14 which moves against 55

the action of a tension spring 20 actuates a drive member 12 (Figs. 1 to 3) or 23 (Figs. 4 to 6) through a link rod 18, which drive member actuates a transmission lever 11. To the transmission lever 11 there is pivoted at 10 an intermediate member 9 carrying a small or fly weight 8. In the two first shown constructional forms of the invention, the intermediate member 9 preferably engages the rear link 5 of the type bar 1 and is also pivotally connected thereto.

The two types 2 associated with a key 14a are preferably arranged on a common type head 2a. The arrangement of the type bars 1 is such that in their positions of rest or normal position (Figs. 1 and 4) all the type heads 2a lie in an approximately horizontal plane in front of the center of the platen 42 in an arc of approximately 90°. The type heads 2a are arranged as closely as possible to the printing point which corresponds to nearly the center of this arc, so that the radius of the arc is a function of half the number of the types 2, the width of the type heads 2a, and the minimum separation between them.

Each type bar 1 is so connected with its two links 3 and 5 that they form therewith a jointed quadrangle. The arrangement is such that the type bar 1 is so guided by the links 3 and 5 in its movement initiated by striking the key 14a, that the types 2 move in an approximately linear path from the normal position (Figs. 1 and 4) to the printing position (Figs. 3 and 6).

In this manner the path of the individual types 2 between the normal and printing positions is maintained as short as possible. This enables the speed of impact of the types in printing to be low, thus greatly reducing the noise of impact. The driving and transmission members are located below the type bars 1 which reduces the size of the machine.

The fixed stop limiting the movement of the key 14 and the drive member 12 consists, in the first form of construction according to Figs. 1 to 3, of a stop pin 30 fixed in the bracket of the machine frame, which pin extends through an opening 27 in the drive member 12, and in the two end positions of the drive members 14a, 14, 13 and 12 it contacts with opposite sides of the opening respectively.

In this construction the drive member 12 is a curved arm, the curve of which, when the key 14a is struck, rolls upon an upper curved portion of an extension 17 of the transmission lever 11, thereby rocking the latter in clockwise direction. The striking movement of the key 14a and the drive members 14, 13 and 12 is arrested by the contact of one side of the opening 27 against the fixed pin 30. The drive member 12 is thus brought into the lower position shown in Fig. 2, and remains in this position while the transmission lever 11 and the parts 9, 8, 5, 1, 3, 2a and 2 associated therewith advance owing to their momentum and without further key action, into the striking position shown in Fig. 3.

To prevent overthrow of the transmission members, that is, an excess movement of the individual elements thereof under the action of momentum beyond the position corresponding to the striking position, and to avoid breaking the toggle joint formed by the members 5 and 1, a projection 21 is provided on the transmission lever 11 which cooperates with the tail 18 of the drive member 12. The striking of this projection 21 against the tail 18 prevents overthrow of the members 11, 9 and 5 at the instant of printing beyond the position corresponding to the printing

position of the types 2 and consequent jamming of said members. Furthermore, the return movement of the transmission members is assisted and accelerated under the action of a tension spring 19 connected to a lug 22 of the lever 11.

After the return of the drive and transmission members to the position of rest or normal position, Fig. 1, the tail 18 of the drive member 12 lies adjacent the end of the lug 22, which prevents the drive and transmission members from rebounding from normal position and vibrating after they have returned thereto. The return movement of the type bars 1 is also further controlled by means of dogs 15 on the type bars 1 which engage elastic pads 16 when the members return from the striking position (Fig. 3) to the normal position (Fig. 1).

In the form of construction shown in Figs. 4 to 6, the drive member consists of a cam 23 having a hook-shaped body 24 as shown in the drawings. The opening 25 of the hook-shaped cam 23 cooperates with a driver pin or roll 26 on the transmission lever 11.

Actuation of the key 14a causes the key lever 14 and the link 13 to effect a clockwise shifting of the cam 23 and the curve of the hook opening 25 engages the roll 26 on the transmission lever 11 to cause the latter also to move clockwise. The mechanism is thereby brought into the position shown in Fig. 5, corresponding to the position shown in Fig. 2 of the first form of construction. The key 14a has then reached its lowermost position.

The cam 23 has a notch 27a bounded by two shoulders 28 and 29. In normal position, Fig. 4, the shoulder 28 lies in contact with a stop pin 30a fixed to the frame bracket 7, and in the intermediate position shown in Fig. 5, the shoulder 29 makes contact with this pin. Downward movement of the key 14a and the corresponding movement of the other drive members 14, 13 and 23 is thus arrested by the shoulder 29 striking the fixed stop pin 30a. The transmission members 11 and 9, the links 5 and 3, and also the type bars 1 along with the type heads 2a, are then advanced by momentum, assisted by the fly weight 8, into the position shown in Fig. 6, in which one of the types 2 contacts against the platen 42.

Excess movement of the transmission members 11, 9 and 5 beyond the position corresponding to printing position of the types 2, and consequent overthrow and jamming of the members and breaking of the toggle joint formed by the members 5 and 1, is prevented in the construction of Figs. 4 to 6, by the pin or roll 26 of the transmission lever 11 being arrested by the hook-shaped portion 24 of the cam 23.

In the normal position of the drive and transmission members, Fig. 4, the roll 26 on the transmission lever 11 lies between the end 25a of the hook opening 25 and the upper end of the hook-shaped portion 24 of the cam 23. By cooperation of the stop members 24, 25a and 26, the mechanism, after completed return from striking position of Fig. 6 to normal position of Fig. 4, is prevented from rebounding from this position and from vibration, as in the construction shown in Figs. 1 to 3 and described in the foregoing.

In the third constructional form illustrated in Figs. 7 and 8, the type bars 1, each of which carries a type head 2a having two types 2, are so arranged that the type heads 2a in their normal position (Fig. 7) lie in an approximately horizontal plane in front of the axis of the platen 42, and occupy an arc of about 90°. The distance of the

types 2 from the printing point 41 is thus a function of half the number of the types 2, the width of the type heads 2a and the minimum separation between the latter. The type bars 1' are each supported by a front link 3' and a rear link 5a. The front link 3' is pivoted at 37 to the machine frame and at 38 to the type bar 1', while the rear link is pivoted at 35 to the machine frame and at 36 to the type bar 1'. The type bars 1' in the normal position shown in Fig. 7, assume a backwardly inclined position, in which their middle and rear portions extend below the horizontal plane through the center of the platen.

The pivotal connections 36 and 38 of the links 5a and 3', and the middle and rear part of the type bar 1 move in an arcuate path from the normal position of Fig. 7 into the printing position of Fig. 8, while the fore part of the type bar 1', the head 2a and the types 2 move in an approximately linear path to the printing point 41 on the platen 42.

This arrangement makes it possible to bring the whole drive mechanism closer to the platen 42 and to reduce the space required to accommodate the movement of the drive and transmission members, the type bars 1', and the links 3' and 5a. Owing to the arcuate movement of the middle and rear portions of each type bar 1', it is possible to guide each type bar during its entire striking movement in a particularly advantageous manner, thus preventing any lateral deviation. According to the present invention the middle and rear parts of the type bar 1' are guided for this purpose in a curved guide 44 corresponding to their arc shaped path. In addition to a reliable striking movement and minimum wear of the joints, this effective guidance through the entire path of movement of the type bars 1' makes it possible for the type bars 1' and the links 3' and 5a supporting the same to be made very thin.

The drive of each type bar 1' is effected by means of its associated key 14a, the corresponding key lever 14, the link 13' and the drive member 23'. The movement of the key 14a is transmitted by the driver member 23' to the transmission members 11', 9 and 5b, which latter during the final portion of the printing movement, are relieved of the action of the key and are brought into printing position, Fig. 8, by momentum, assisted by the fly weight 8. The last member 5b of the transmission mechanism does not directly engage the type bar 1', as in the other two forms of construction, but constitutes a toggle lever with a separate drive bar 45. This drive bar is preferably so arranged that it engages the type bar 1' at a point located between the type head 2a and the joint 38 of the front link 3'. This arrangement provides a very favorable transmission of force whereby the force is applied directly in the direction of movement and striking of the types 2, and in close proximity to the types. This is the case both during the movement of the type bars resulting from striking the key 14a, and during the movement under their momentum and the action of the fly weights 8. By means of this arrangement the drive rod 45 together with the guiding of the type bar 1' by the guide 44 permit increased accuracy of the approximately linear striking movement of the types 2 against the platen 42.

The joints 35, 36, 37 and 38 of the two links 5a and 3' are so arranged that in the striking position, Fig. 8, the intersection of the line 39 connecting the joints 35 and 36 of the link 5a with

the line 40 connecting the joints 37 and 38 of the link 3', lies in a plane 43, which is tangential with the printing point 44 on the platen 42.

This arrangement of the joints 35, 36, 37 and 38 causes the impact of the types 2 against the platen 42 to take place always exactly in the direction of the axis of the platen whereby slipping of the types on the paper is prevented and sharp impression of the type, without blurring, is achieved even when a large number of copies are made.

The operation of the parts 23', 24', 25', 26', 27' and 30' is similar to that of the parts 23, 24, 25, 26, 27 and 28, respectively, shown in Figs. 1 to 6.

I claim as my invention:

1. A typewriter comprising a machine frame; a platen; a plurality of keys; a plurality of type bars; a pair of links for each type bar; drive and transmission means between each key and its type bar for operating the type bar by its key; a fixed bearing on the machine frame for the end of each of said links to provide a pivotal mounting for each link, each type bar being driven by a single key from its position of rest only to a position just in front or before the printing position its further movement to the printing position being effected by momentum forces; and a set of types of which two types are attached on each type bar, said types being arranged in the position of rest in two rows forming circular arcs of approximately 90° lying one above the other in planes substantially horizontal and parallel to and extending in front of the axis of the platen.

2. A typewriter according to claim 1, in which stop members are provided on the drive and transmission means cooperating with each key and its type bar to prevent an overthrow of the parts beyond the position corresponding to the printing position of the types.

3. A typewriter according to claim 1, in which stop members are provided on the drive and transmission means cooperating with each key and its type bar to prevent an overthrow of the parts beyond the position corresponding to the printing position of the types and a rebound of the parts from the position of rest after having returned from the printing position, the stop on a drive member being in the form of a tail piece.

4. A typewriter according to claim 1, in which stop members are provided on the drive and transmission means cooperating with each key and its type bar to prevent an overthrow of the parts beyond the position corresponding to the printing position of the types and a rebound of the parts from the normal position of rest after having returned from the printing position, the stop on a drive member being in the form of a hook-shaped body.

5. A typewriter according to claim 1, in which stop members are provided on the drive and transmission means cooperating with each key and its type bar to prevent an overthrow of the parts beyond the position corresponding to the printing position of the types and a rebound of the parts from the position of rest after having returned from the printing position, the movement of the transmission means, when the printing position is reached and after return from that position to the position of rest, being limited by engagement between projections on a transmission lever with correspondingly shaped parts on a drive member.

6. A typewriter according to claim 1, in which the pivotal connections of the links with the type

bars and the machine frame are so arranged that the middle and rear part of each type bar during its movement from the position of rest to printing position traverses an arc-shaped path and its type head moves through an approximately linear path.

7. A typewriter according to claim 1, in which the pivotal connections of the links with the type bars and the machine frame are so arranged that the middle and rear part of each type bar during its movement from the position of rest to printing position traverses an arc-shaped path and its type head moves through an approximately linear path, and in which a curved guide is provided for each type bar to guide the type bar in its arcuate path.

8. A typewriter according to claim 1, in which the pivotal connections of the links with the type bars and the machine frame are so arranged that the middle and rear part of each type bar during its movement from the position of rest to printing position traverses an arc-shaped path and its type head moves through an approximately linear path, and in which a curved guide is provided for each type bar to guide the type bar in its arcuate path and a drive bar is connected to each type bar and to the transmission means to actuate the type bar.

9. A typewriter according to claim 1, in which the pivotal connections of the links with the type bars and the machine frame are so arranged that the middle and rear part of each type bar during its movement from the position of rest to printing position traverses an arc-shaped path and its type head moves through an approximately linear path, and in which a curved guide is provided for each type bar to guide the type bar in its arcuate path, and a drive bar is pivotally connected at one end to each type bar at a point of the latter between the type head and the next link connection and at the other end to the transmission means to actuate the type bar.

10. A typewriter according to claim 1, in which the pivotal connections of the links with the type bars and the machine frame are so arranged that

the middle and rear part of each type bar during its movement from the position of rest to printing position traverses an arc-shaped path and its type head moves through an approximately linear path, the joints of the pivotal connections for the links of each link forming lines in the printing position which intersect in a plane tangential to the platen at the printing point.

11. A typewriter according to claim 1, in which stop members are provided on the drive and transmission means cooperating with each key and its type bar to prevent a rebound of the parts from the position of rest after having returned from the printing position.

12. A typewriter having keys and a platen, and provided with type bars, two links for controlling each bar, said type bars being freed, at the point of printing, from the action of the said keys and caused to print by momentum forces, wherein each type bar has a head carrying two types, said heads being arranged, in the position of rest, in a circular arc of approximately 90° extent in a plane lying approximately horizontal in front of the center of the typewriter platen at a distance from the printing point which is as small as possible, and dependent upon the number of type heads, means whereby said heads are moved by means of the aforesaid links in approximately linear paths up to the printing point, including drive and transmission members for actuating the type bars, said type bars being pivotally connected with said links, said transmission members being connected with operating bars which engage against the portions of the type bars which lie between the type heads and the pivotal connections of the type bars with the forward links.

13. A typewriter according to claim 1, in which the drive and transmission means include a drive member actuating a transmission lever by means of a curved cam surface and a roll running on said surface.

bars and the machine frame are so arranged that the middle and rear part of each type bar during its movement from the position of rest to printing position traverses an arc-shaped path and its type head moves through an approximately linear path.

7. A typewriter according to claim 1, in which the pivotal connections of the links with the type bars and the machine frame are so arranged that the middle and rear part of each type bar during its movement from the position of rest to printing position traverses an arc-shaped path and its type head moves through an approximately linear path, and in which a curved guide is provided for each type bar to guide the type bar in its arcuate path.

8. A typewriter according to claim 1, in which the pivotal connections of the links with the type bars and the machine frame are so arranged that the middle and rear part of each type bar during its movement from the position of rest to printing position traverses an arc-shaped path and its type head moves through an approximately linear path, and in which a curved guide is provided for each type bar to guide the type bar in its arcuate path and a drive bar is connected to each type bar and to the transmission means to actuate the type bar.

9. A typewriter according to claim 1, in which the pivotal connections of the links with the type bars and the machine frame are so arranged that the middle and rear part of each type bar during its movement from the position of rest to printing position traverses an arc-shaped path and its type head moves through an approximately linear path, and in which a curved guide is provided for each type bar to guide the type bar in its arcuate path, and a drive bar is pivotally connected at one end to each type bar at a point of the latter between the type head and the next link connection and at the other end to the transmission means to actuate the type bar.

10. A typewriter according to claim 1, in which the pivotal connections of the links with the type bars and the machine frame are so arranged that

the middle and rear part of each type bar during its movement from the position of rest to printing position traverses an arc-shaped path and its type head moves through an approximately linear path, the joints of the pivotal connections for the links of each link forming lines in the printing position which intersect in a plane tangential to the platen at the printing point.

11. A typewriter according to claim 1, in which stop members are provided on the drive and transmission means cooperating with each key and its type bar to prevent a rebound of the parts from the position of rest after having returned from the printing position.

12. A typewriter having keys and a platen, and provided with type bars, two links for controlling each bar, said type bars being freed, at the point of printing, from the action of the said keys and caused to print by momentum forces, wherein each type bar has a head carrying two types, said heads being arranged, in the position of rest, in a circular arc of approximately 90° extent in a plane lying approximately horizontal in front of the center of the typewriter platen at a distance from the printing point which is as small as possible, and dependent upon the number of type heads, means whereby said heads are moved by means of the aforesaid links in approximately linear paths up to the printing point, including drive and transmission members for actuating the type bars, said type bars being pivotally connected with said links, said transmission members being connected with operating bars which engage against the portions of the type bars which lie between the type heads and the pivotal connections of the type bars with the forward links.

13. A typewriter according to claim 1, in which the drive and transmission means include a drive member actuating a transmission lever by means of a curved cam surface and a roll running on said surface.
